UNITED STATES PATENT OFFICE.

JOHN R. WARREN, OF GRAND RAPIDS, MICHIGAN.

INTERNAL-COMBUSTION ENGINE.

1,278,533.

Specification of Letters Patent. Patented Sept. 10, 1918.

Application filed July 19, 1917. Serial No. 181,482.

To all whom it may concern:

Be it known that I, JOHN R. WARREN, a citizen of the United States, residing at Grand Rapids, in the county of Kent and State of Michigan, have invented new and useful Improvements in Internal-Combustion Engines, of which the following is a specification.

The present invention relates to internal combustion engines; and its object is to provide an improved rotary valve for a four-stroke-cycle engine which shall not be subject to binding or sticking due to heating; and further, such a valve having a plurality of longitudinally extending exhausting passages spaced apart; and further, such a valve having such exhausting passages spaced apart by a passage; and further, such a valve having a passage communicating with the carbureter so that air may be drawn through said passage to cool the exhausting passage and then forced warm into the carbureter; and further, to provide such a valve into whose exhausting passages the same cylinder exhaust alternately; and further, to provide in such an engine, means whereby a desired amount of air drawn through the valve's air passage may be diverted from the carbureter, another amount being forced thereinto; and further, to provide such a valve whose openings, ports and passages may be identical on opposite sides of its axis, whereby the valve may be economically cast in a mold; and further, to provide improved means for connecting the rotary valve with the engine's exhaust pipe.

These objects are attained by, and the invention finds preferable embodiment in, the structure hereinafter particularly described and illustrated by the accompanying drawings, in which:

Figure 1 is an end view of a four-stroke-cycle internal combustion engine having four cylinders, the end cap of the gear housing being removed and the position of gears being indicated;

Fig. 2 is a longitudinal sectional view of the same taken on planes corresponding to line 2-2 of Fig. 3;

Fig. 3 is a transverse sectional view of the same taken on a plane corresponding to line 3-3 of Fig. 2; and

Fig. 4 is a view of adjustable air connections leading to the carbureter.

In the embodiment of the invention chosen for illustration by the drawings and

for detailed description in the body of this specification, the pistons (one of which appears at 2) of the internal combustion engine 1 of the usual "four-stroke-cycle type," have connecting rods 5, 6, 7, 8 for revolving the crank shaft 9. This shaft with its cranks is inclosed in a casing 10 adapted to contain a lubricant. The engine rotary valve 12 bears in a continuous valve chamber 13 and is driven (one revolution to the crank shaft's four revolutions) by suitable means as by the gears, 50 on the crank shaft, 51 and 52 rotating together as one on a spindle 53, and 54 on the shaft 57. The valve chamber has a combustible fluid inlet 20 from the carbureter 55, and ports 21, 22, 23, 24 leading to the engine cylinder respectively. The valve 12 has an intaking passage comprising an annular depression 25, into which said inlet 20 directly opens, such depression opening into the intaking passage's portions 26, 27 on either side: these portions 26, 27 are arcuate in cross section and concentric with the axis of the valve, and have two diametrically opposite outlets 28, 56 to each cylinder and alternately opening to said cylinder during its intaking stroke. These outlets 28 to cylinders 1 and 2 are preferably alined and so are the outlets 56 to said cylinders; and the outlets 28 to cylinders 3 and 4 are preferably alined, as are the outlets 56 to said cylinders, the outlets 28 to cylinders 1 and 2 being angularly disposed ninety degrees from outlets 28 to cylinders 3 and 4. The valve 12 contains two parallel exhaust passages 58, 66 extending longitudinally of the valve and spaced apart by an air passage 59. The outer wall 60 of each exhaust passage is spaced from the peripheral wall 61 of the valve by the arcuate portions 26, 27 of the combustible fluid intaking passage, and the side walls 62 of each exhaust passage are spaced from said peripheral wall by said air passage, the inner walls 63 of the exhaust passages being wholly spaced apart by said air passage. It is evident that when the exhaust passages become heated, the inner walls 63 may expand toward each other and the side walls 62 of each exhaust passage outwardly from each other (thus contracting the air passage) without appreciably expanding the valve in its chamber and causing it to tighten or bind therein, the outer wall 60 of each exhaust passage similarly expanding and thus contracting the arcuate passages 26, 27.

The valve chamber is provided with alined ports 21, 24 communicating with the first cylinder 64 and the fourth cylinder, and alined ports 22, 23 communicating with 5 the second and third cylinders, for the intaking of the combustible fluid and the exhausting of the products of combustion. The ports 21, 24 are angularly disposed forty-five degrees from the ports 22, 23. By 10 the angular disposition as above described of the various openings through the walls of the valve and valve chamber, economy of production is furthered, inasmuch as the sides of the valve on opposite sides its axis 15 are alike, whereby the valve may be easily cast in a mold. Diametrically opposite exhaust ports 67, 68 for each cylinder extend through the peripheral wall 61 of the valve,—67 to the exhaust passage 58 and 68 20 to the exhaust passage 66. These exhaust ports for the first and second cylinders are respectively preferably alined, as are those for the third and fourth cylinders, the ports 67 for the first and second cylinders being 25 angularly disposed ninety degrees from the ports 67 for the third and fourth cylinders. This angular disposition of intakes and exhaust ports in the valve and valve chamber will be varied with the number of cylinders, 30 the above applying to an engine having four cylinders. It will thus be seen that each cylinder intakes combustible fluid twice in the valve's rotation and exhausts twice, once into the valve's exhaust passage 58 and once 35 into the other passage 66 which are diametrically opposite. By this arrangement the valve is evenly heated on opposite sides and its tendency to warp out of axial alinement or to expand unevenly is minimized. 40 Fig. 3 shows the first cylinder 64 just after it has completed its exhaust stroke, the combustion products having been expelled through the port 67 into the valve's exhaust passage 58. When the valve turns 45 so as to open the intake passage 28 to the port 21 the fluid is drawn into this cylinder. Air is drawn by the fan 69, rotated as by gears 54, 70, through the opening 71 and around the branches 58, 66 of the valve's 50 exhaust passage (which discharges at 72), in the direction indicated by the arrows in Fig. 2, during which course it cools the exhaust passages, and is then forced thus warmed through the tube 76 into the carbureter 55 for mixing the combustible fluid. The amount of such air thus forced into the carbureter may be governed by turning the member 74, pivoted at 75 and carrying one 55 end of the flexible air tube 76, so as to register in greater or less degree the mouth of this tube 76 with the opening 77 of the fan's discharge pipe 78.

The outer end 79 of the valve is spaced from the wall of the orifice 80 through 60 which it extends, so that when expanded by

heating it may not contact therewith. A chamber 81, separated from the valve chamber, and having an outlet 82, is adapted to receive any of the products of combustion which might otherwise run inwardly along 70 the outside of the exhaust's nozzle 72 and into the valve chamber. Orifices for spark plugs are shown at 83, the engine fly-wheel at 84, and water jackets at 85.

A connection of the valve's casing with 75 the exhaust pipe 86 of the engine is shown at the left hand side of Fig. 2. It will be seen from this view that although the valve rotates, a closed connection between the engine's exhaust and the muffler (not shown) 80 or the outside air, is provided, and that too although the valve's nozzle 72 does not bear where the connection with the pipe 86 is made.

The invention being intended to be 85 defined solely by the claims is not to be limited to or by details of construction shown or described.

I claim:

1. In a four-stroke-cycle internal combustion engine having a plurality of engine cylinders; a valve chamber having an inlet and ports to the cylinders respectively; a rotary engine valve, bearing in said chamber and having an intaking passage communicating with said inlet, said passage having outlets communicating with the ports respectively in certain positions of the valve; the valve having also a plurality of exhausting passages extending longitudinally of the valve and communicating with all the cylinders respectively in certain positions of the valve, and with their adjacent walls spaced apart; inlets to the exhausting 90 passages communicating with the ports respectively. 95

2. In a four-stroke-cycle internal combustion engine having a plurality of engine cylinders; a valve chamber having an inlet and ports to the cylinders respectively; a rotary engine valve, bearing in said chamber and having an intaking passage communicating with said inlet, said passage having outlets communicating with the ports respectively in certain positions of the valve; the valve having also a plurality of exhausting passages extending longitudinally of the valve and communicating with all the cylinders respectively in certain positions of the valve, and spaced apart by a 100 passage for cooling fluid; inlets to the exhausting 105 passages communicating with the ports respectively. 110

3. In a four-stroke-cycle internal combustion engine having a plurality of engine cylinders; a valve chamber having an inlet and ports to the cylinders respectively; a rotary engine valve, bearing in said chamber and having an intaking passage communicating with said inlet, said passage having 115

- outlets communicating with the ports respectively in certain positions of the valve; the valve having also a plurality of exhausting passages extending longitudinally 5 of the valve and communicating with all the cylinders respectively in certain positions of the valve, and spaced apart by a passage for cooling fluid; inlets to the exhausting passages communicating with the ports respectively; and means for forcing a cooling fluid through the said passage therefor. 10

4. In a four-stroke-cycle internal combustion engine having a plurality of engine cylinders and a carbureter; a valve chamber 15 having an inlet and ports to the cylinders respectively; a rotary engine valve, bearing in said chamber and having an intaking passage communicating with said inlet, said passage having outlets communicating with the ports respectively in certain positions of the valve; the valve having also a plurality of exhausting passages extending longitudinally of the valve and communicating with all the cylinders respectively in 20 certain positions of the valve, and spaced apart by an air passage having a continuation extending to the carbureter; inlets to the exhausting passages communicating with the ports respectively; means for forcing air through the air passage and thence into the carbureter. 25

5. In a four-stroke-cycle internal combustion engine having a plurality of engine cylinders and a carbureter; a valve chamber 30 having an inlet and ports to the cylinders respectively; a rotary engine valve, bearing in said chamber and having an intaking passage communicating with said inlet, said passage having outlets communicating with the ports respectively in certain positions of the valve; the valve having also a plurality of exhausting passages extending longitudinally of the valve and communicating with all the cylinders respectively in certain positions of the valve; inlets to each exhausting passage communicating with the port to each cylinder. 35

outlets communicating with the ports respectively in certain positions of the valve; the valve having also a plurality of exhausting passages extending longitudinally of the valve and communicating with all the cylinders respectively in certain positions of the valve, and an air passage having a continuation extending to the carbureter; inlets to the exhausting passage communicating with the ports respectively; means for forcing air through the air passage and thence to the carbureter. 70

7. In a four-stroke-cycle internal combustion engine having a plurality of engine cylinders; a valve chamber having an inlet and ports to the cylinders respectively; a rotary engine valve, bearing in said chamber and having intaking passages communicating with said inlet, said passages having outlets communicating with the ports respectively in certain positions of the valve; the valve having also a plurality of exhausting passages extending longitudinally of the valve and spaced apart by an air passage and spaced from the valve's peripheral wall by the valve's intaking passages; inlets to the exhausting passages communicating with the ports respectively. 80

8. In a four-stroke-cycle internal combustion engine having a plurality of engine cylinders; a valve chamber having an inlet and ports to the cylinders respectively; a rotary engine valve, bearing in said chamber and having intaking passages communicating with said inlet, said passages having outlets communicating with the ports respectively in certain positions of the valve; the valve having also a plurality of exhausting passages extending longitudinally of the valve and communicating with all the cylinders respectively in certain positions of the valve; inlets to each exhausting passage communicating with the port to each cylinder. 90

9. In a four-stroke-cycle internal combustion engine having a plurality of engine cylinders and a carbureter; a valve chamber having an inlet and ports to the cylinders respectively; a rotary engine valve, bearing in said chamber and having an intaking passage communicating with said inlet, said passage having outlets communicating with the ports respectively in certain positions of the valve; the valve having also an exhausting passage extending longitudinally of the valve and an air passage having a continuation; a flexible pipe communicating with the carbureter at one end; a turnable member to which the other end of said pipe is attached and adapted to be turned to bring its end of said pipe into greater or less registration with the mouth of the air passage's continuation. 100
